(57) **CLAIM**

The ornamental design for a recharger of an internal neuralstimulator, as shown and described.

DESCRIPTION

FIG. 1 is a top perspective view of a recharger of an internal neuralstimulator showing my new design.

FIG. 2 is a top plan view thereof.

FIG. 3 is a bottom plan view thereof.

FIG. 4 is a right side elevation view thereof.

FIG. 5 is a left side elevation view thereof.

FIG. 6 is an end elevation view thereof.

FIG. 7 is another end elevation view thereof; and,

FIG. 8 is a bottom perspective view thereof.

In the drawings, the broken lines depict portions of the recharger of an internal neuralstimulator that form no part of the claimed design.
